(57) **CLAIM**

The ornamental design for a magazine cover, as shown and described.

DESCRIPTION

FIG. 1 is a first perspective view of a magazine cover showing my new design;

FIG. 2 is a second perspective view of a magazine cover showing my new design;

FIG. 3 is a first side elevation view thereof;

FIG. 4 is a second side elevation view thereof;

FIG. 5 is a third side elevation view thereof;

FIG. 6 is a fourth side elevation view thereof;

FIG. 7 is a top plan view thereof; and,

FIG. 8 is a bottom plan view thereof.

The broken lines in FIGS. 1-8 are for the purpose of illustrating features of the magazine cover that form no part of the claimed design.

1 Claim, 5 Drawing Sheets(56)
